INTERNAL COMBUSTION ENGINE

August A. Filicky, San Francisco, Calif.

Application March 17, 1937, Serial No. 131,382

4 Claims. (Cl. 123—54)

This invention relates particularly to a multi-cylinder, four cycle internal combustion engine having a plurality of cylinders therein, said cylinders being disposed in the engine block in pairs throughout the length thereof with the vertical axes of all the cylinders parallel to each other.

A further object of the invention is to provide an internal combustion engine of the multi-cylinder type wherein the cylinders are arranged in parallel pairs, each cylinder having its own piston and connecting rod therein, and each of the connecting rods being rotatably mounted in offset relation to each other and in eccentric relation to a crank shaft rotatably mounted in the crank case of the engine.

A still further object of the invention is to provide an internal combustion engine having a crank shaft journaled therein, the said crank shaft having a pair of related throws thereon, each of which are separated radially relative to each other and eccentrically relative to the center of the crank shaft, whereby the connecting rods of a pair of parallel reciprocating pistons will function to reciprocate said pistons in the same path of travel at all times.

Other objects of the invention are to provide a multi-cylinder internal combustion engine of the four cycle type including pairs of cylinders arranged in parallel rows, wherein the piston in one cylinder on the downward stroke will suck a combustible mixture into the cylinder simultaneously with the firing of the combustible mixture in the other cylinder, to effect the downward movement of the piston in that cylinder, and to provide an internal combustion engine that will be superior in point of simplicity, inexpensiveness of construction, positiveness of operation, and facility and convenience in use and general efficiency.

In this specification and the annexed drawings, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

In the accompanying drawings:

Fig. 1 represents a diagrammatic view of an internal combustion engine constructed in accordance with my invention, a portion thereof being broken away to show the interior construction thereof.

Fig. 2 is a vertical cross section taken through Fig. 1 on the line 2—2.

Fig. 3 is a side elevation of the piston connecting rod and crank shaft assembly of one of the cylinder units.

Fig. 4 is a front elevation of a section through two of the parallel cylinders showing the piston and connecting rod assembly in the uppermost position, and particularly illustrating the offset connection of the connecting rods and crank shaft.

Fig. 5 is a diagrammatic view showing the pistons and connecting rods during the various phases of their movements.

In detail the construction illustrated in the drawings comprises the engine block 1, crank case 2, cylinder head 3, crank shaft 4, connecting rods 5, and pistons 6. The engine block throughout its length is provided with a plurality of cylinders 7, there being two rows of cylinders 7, one on each side of the longitudinal center line of the engine block, thus providing multi-pairs of cylinders 7 on both sides of the vertical center line of the engine block. Both the engine block 1 and cylinder head 3 are water jacketed for cooling purposes, and the engine block is ported with the usual gas intake passages and exhaust gas passages, together with the valves 8, cam shafts 9 and spark plugs 10, all of which are conventional and all of which are necessary to the operation of an internal combustion engine. Each cylinder, and all of the operative parts, functions on the four cycle principle.

The crank shaft 4 beneath each pair of cylinders 7—7 is provided with parallel disks 11 and the lower end of each of the connecting rods 5 is rotatably mounted on the throw 12 which extends between each of the pairs of plates 11. The throws 12 are mounted radially between the plates 11 with respect to the center axis of the crank shaft 4 and are likewise located eccentrically relative to said crank shaft axis. Each of the throws 12 between the pairs of plates 11, likewise have their centers offset or spaced apart, whereby the rotation of the crank shaft will cause the pistons on the upper ends of the connecting rods 5 to lie in substantially the same aligned plane during the reciprocative movement thereof. In other words each of the pistons 6 will reach the upper and lower limits of their reciprocative movements at precisely the same time, and in addition will be substantially flush with each other at intermediate positions of the reciprocative movement. Each of the connecting rods 5 are offset in two directions throughout their length

to compensate for the off-center arrangement between the crank throws and the wrist pins of the pistons.

In the operation of the engine all of the engine parts are timed to operate in the usual four cycle sequence so that the piston in one cylinder of each pair can be moving downwardly on its firing stroke while the other piston on the same pair is moving downwardly on its suction stroke, and vice versa. Similarly on the up stroke of the pistons, one would be proceeding on the compression stroke while the other would be on the exhausting stroke and vice versa.

The firing arrangement of the engine would be such that it would pass alternately back and forth across the longitudinal center line of the block. Likewise, with my construction it is only necessary to have but a single gas intake to serve two cylinders in contradistinction to the conventional form of V-type engine wherein it is necessary to have a separate intake for each cylinder. In the conventional V-type engine, the piston, connecting rod, and crank shaft arrangement is such that each piston operates in a differentially timed relation to the piston directly opposite, whereas in my construction both pistons operate at the same time, and the power impulse directed against one piston is not retarded or minimized by the inertia of the piston directly opposite. In the ordinary V-type engine, a power impulse directed against one piston is to a certain extent reduced in efficiency by the lag of the piston directly opposite which, because of the timing and cycle of operation, is not in a position to commence its downward stroke with the piston to which the power impulse has been applied, and likewise, the same result is true on the up-stroke of the respective pistons.

With my invention, both pistons are timed to work together during all phases of operation and I have so timed the cycle of operation of the pistons that on the firing stroke of either piston, the other piston does not tend to lag, and hence increases the operating efficiency of the engine.

Having thus described this invention, what I claim and desire to secure by Letters Patent is:

1. In an internal combustion engine, a cylinder block having plural pairs of parallel cylinders each of the cylinders of each pair lying opposite each other on a transverse plane at right angles to and on each side of the center line of the engine crank shaft, pistons slidably mounted in said cylinders; a crank shaft, a pair of offset throws on said crank shaft in substantial alignment with each pair of cylinders; and a connecting rod having a right angle and laterally offset bend between each piston and matching crank shaft throw whereby the respective

pistons will be in substantially corresponding positions in the pair of cylinders during every phase of the cycle of operation.

2. The combination with an internal combustion engine having plural pairs of parallel cylinders each of the cylinders of each pair lying opposite each other on a transverse plane at right angles to and on each side of the center line of the engine crank shaft, pistons slidably mounted in said cylinders; a crank shaft having a pair of eccentric and offset throws approximately opposite each pair of cylinders; and a rod having a right angle and laterally offset bend connecting each piston with one of the opposite throws whereby the respective pistons will move in substantially corresponding positions in the pair of cylinders during the reciprocative movements of said pistons.

3. The combination with an internal combustion engine having plural pairs of parallel cylinders each of the cylinders of each pair lying opposite each other on a transverse plane at right angles to and on each side of the center line of the engine crank shaft; pistons slidably mounted in said cylinders; a crank shaft journaled lengthwise of and eccentrically between and beneath the pairs of parallel cylinders having a pair of eccentric and offset throws approximately opposite each pair of cylinders; and a rod having a right angle and laterally offset bend connecting each piston with one of the opposite throws whereby the respective pistons will move in approximately corresponding positions in the pair of cylinders during the reciprocative movements of said pistons.

4. The combination with an internal combustion engine having a pair of cylinders arranged with their central axes parallel, each of the cylinders of each pair lying opposite each other on a transverse plane at right angles to and on each side of the center line of the engine crank shaft; of a crank shaft arranged below and centrally between said cylinders; a pair of eccentric throws on said crank shaft, each being offset relative to the other; pistons in said cylinders; and a rod having a right angle and laterally offset bend connecting each of said pistons to one of said crank throws whereby rotative movement of the crank shaft causes the respective pistons to lie in the same corresponding aligned position at the upper and lower limits of the reciprocative strokes, and permitting the firing and suction strokes and the compression and exhaust strokes of the pair of pistons to occur during exactly the same periods before the four cycle operation of the engine.

AUGUST A. FILICKY.
